UNITED STATES PATENT OFFICE

98,061

DESIGN FOR A ROTARY VALVE

Victor E. Flodin, Oak Park, Ill., assignor to Crane
Co., Chicago, Ill., a corporation of Illinois

Application October 30, 1935, Serial No. 59,272

Term of patent 14 years

To all whom it may concern:

Be it known that I, Victor E. Flodin, a citizen of the United States residing at Oak Park, in the county of Cook and State of Illinois, whose post-office address is 1037 North Kenilworth Avenue, Oak Park, Illinois, have invented a new, original, and ornamental Design for a Rotary Valve, of which the following is a specification, reference being had to the accompanying drawing, forming part thereof.

The drawing illustrates a perspective view of a rotary valve embodying my design, the dominant feature of which is an enclosure superposed upon a yoke housing and supported by a valve bonnet. The side not shown is identical with the side shown.

I claim:

The ornamental design for a rotary valve substantially as shown and described.

VICTOR E. FLODIN.
